(57) **CLAIM**

I claim the ornamental design for a multimedia wedge, as shown and described.

DESCRIPTION

FIG. 1 is a front, top and right perspective view of the multimedia wedge;

FIG. 2 is a front elevational view thereof;

FIG. 3 is a rear elevational view thereof;

FIG. 4 is a right elevational side view thereof;

FIG. 5 is a left elevational side thereof;

FIG. 6 is a top plan view thereof; and,

FIG. 7 is a bottom plan view thereof.

The broken lines in the drawings depict portions of the multimedia wedge that form no part of the claimed design.
